Morel

(10) **Patent No.:** **US D607,763 S**
(45) **Date of Patent:** **** Jan. 12, 2010**

(54) **ELECTRICAL VOLTAGE OR CURRENT
SENSOR**

(75) Inventor: **Pascal Morel**, Saint Pierre en Faucigny
(FR)

(73) Assignee: **Liaisons Electroniques-Mechaniques.**
(CH)

(**) Term: **14 Years**

(21) Appl. No.: **29/325,925**

(22) Filed: **Oct. 8, 2008**

(30) **Foreign Application Priority Data**

Apr. 8, 2008 (CH) 2008/00346

(57) **CLAIM**

The ornamental design for an electrical voltage or current
sensor, as shown and described.

DESCRIPTION

FIG. 1 is a top perspective view of the first embodiment of the
sensor from a first end;

FIG. 2 is a top perspective view of the sensor of FIG. 1 from
a second end;

FIG. 3 is a bottom view of the sensor of FIG. 1;

FIG. 4 is an end view of the sensor of FIG. 1;

FIG. 5 is a top elevational view of the sensor of FIG. 1;

FIG. 6 is a right side view of the sensor of FIG. 1;

FIG. 7 is a right side view of the sensor of FIG. 1;

FIG. 8 is an end view of the sensor of FIG. 1;

FIG. 9 is a top perspective view of the second embodiment of
the sensor from a first end;

FIG. 10 is a top perspective view of the sensor of FIG. 9 from
a second end;

FIG. 11 is a bottom view of the sensor of FIG. 9;

FIG. 12 is an end view of the sensor of FIG. 9;

FIG. 13 is a top elevational view of the sensor of FIG. 9;

FIG. 14 is a right side view of the sensor of FIG. 9;

FIG. 15 is a right side view of the sensor of FIG. 9; and,

FIG. 16 is an end view of the sensor of FIG. 9.
